UNITED STATES PATENT OFFICE

HARVEY HUBBELL, JR., OF BRIDGEPORT, CONNECTICUT

SOCKET SHELL AND SHADE HOLDER

Application filed October 27, 1927. Serial No. 229,038.

This invention relates to an electric lamp socket construction, and particularly to improved means for mounting a lamp shade thereon, and has for an object to provide a lamp socket shell and shade frame construction which is very simple and economical in construction, may be easily manipulated to apply or remove the frame, and which when in normal working condition the frame is positively secured to the shell so that it cannot be easily disconnected therefrom.

With the foregoing and other objects in view, I have devised the construction illustrated in the accompanying drawing forming a part of this specification. In this drawing,

Fig. 1 is a side elevation of a lamp socket shell and shade applied thereto, a portion of the shell and shade being broken away to more clearly show the construction.

Fig. 2 is a partial side elevation and partial section of the shell showing the position of the lining while applying the shade frame to the shell or removing it therefrom, and also indicating the frame as about to be applied to the shell.

Fig. 3 is a side elevation of the lower portion of the shell and a section through the supporting ring of the frame showing how the same passes over the outer bead of the shell.

Fig. 4 is a plan view of a frame used with this construction, and

Fig. 5 is an end view of the shell.

The lamp socket shown of sheet metal is composed of separable body and cap sections 10 and 11 respectively carrying the usual works of which the insulating block is indicated at 12, the screw shell lamp contact at 13 and switch operating means, such as a key 14. As is usual in this type of devices there is mounted between the shell and the works and screw shell a fibre insulating lining 15 which is ordinarily made of relatively stiff material and as it is substantially cylindrical and is not easily compressed particularly if it is a fairly tight fit in the shell. A common means of securing a shade frame to the shell is by coacting screw threads on the shell and a sleeve carrying the frame. In

the present construction the screw threads are omitted and at its lamp receiving end the shell is provided with a pair of spaced outwardly extending annular ribs or beads 16 and 17 which may be conveniently formed by rolling them in the walls of the shell. The shell is also provided with one or more slits 18 extending longitudinally from this end across the ribs or beads and terminating in perforations 19. These slits will permit the walls of the shell to yield inwardly as will presently be described.

Associated with this shell is a wire shade frame. This frame has a central ring 20 and may have one or more spaced rings 21 of larger diameter depending on the size of the shade to be supported, and these rings are connected by transverse wires 22 which may be butt welded to the rings making a substantial and rigid construction.

In applying the frame to the shell the interior mechanism of the shell is first removed, or the frame may be applied before this mechanism has been mounted in the shell, and the fibre lining 15 is partly withdrawn from the shell, as shown in Fig. 2. The walls of the lower end of the shell may now yield inwardly and the wire frame is applied by merely forcing the ring 20 over the outer bead 17, as shown in Fig. 3, the walls of the shell yielding inwardly to permit this action. As the ring passes beyond this bead the walls of the shell spring outwardly under the resilient action of the shell so that the ring 20 seats in the groove formed between the two beads as indicated in Fig. 1, and it is preferred that the two beads be spaced from each other a distance substantially equal to or slightly less than the diameter of the wire of the ring so that the ring will seat snugly in this groove. After the frame has been applied to the shell the fibre lining 15 may be moved to its normal position as shown in Fig. 1, and the mechanism or works including the screw contact 13 assembled within the shell as indicated in Fig. 1. It will be apparent that when the lining is in this position it lies and fits the shell immediately under the ribs 16 and 17, and will hold the walls of the shell in the normal ex-

panded position under any tendency of the ring 20 acting on the lower rib 17 to force these walls inwardly and permit the ring to separate from the shell under the weight of the shade. The screw contact 13 also assists 5 the fibre lining in holding the walls of the shell in the expanded position to lock the frame to the shell. Any suitable covering or shade 23 may be applied to the frame as 10 desired.

It will be apparent from the foregoing description that the structure is a very simple one and that when the lining and interior mechanism is removed from the shell the 15 shade frame may be easily and quickly applied or removed from the shell, but when this lining and interior mechanism is in normal assembled position the frame is firmly locked to the shell and will sustain considerable weight. The structure is simple and 20 economical, and the frame may be easily turned to bring any particular figure or design on the shade to the front of the lamp without in any way loosening the holder, 25 which is not true in the common form of shade holder in which there are screw threads formed on the shell cooperating with a similarly threaded sleeve for securing the holder to the shell. Also due to the locking effect of the tightly fitting fibre lining and the 30 screw contact this connection will sustain a considerable weight.

Having thus set forth the nature of my invention, what I claim is:

35 1. In a lighting fixture, a socket shell of resilient sheet metal provided adjacent its outer end with a pair of spaced annular ribs and having one or more longitudinal slits extending across the outer rib to permit the 40 walls to yield laterally, and a shade holder frame including a wire ring adapted to seat and be held between the two ribs.

45 2. In a lighting fixture, a lamp socket shell of resilient sheet metal provided on its outer wall adjacent its entrance end with a pair of spaced annular ribs, said shell being also provided with one or more slits extending across said ribs to permit the walls of the shell to yield inwardly, and a shade holder 50 frame including a circular ring adapted to seat and be held between the two ribs.

55 3. In a lighting fixture, a lamp socket shell of resilient sheet metal provided on its outer wall adjacent the lamp end with a pair of spaced annular ribs, said shell being provided with one or more slits extending longitudinally from said end to permit the walls of the shell to yield inwardly, a shade holder frame including a ring adapted to seat between and be held to the shell by said ribs, and a lining for the shell under said ribs and arranged to retain the shell in the expanded condition.

60 4. In a lamp fixture, a lamp socket shell of 65 resilient sheet metal having a pair of out-

wardly extending spaced annular beads adjacent its lamp end, said shell having one or more slits extending longitudinally from said end across the beads to permit the walls of the shell to yield inwardly, a shade holder frame including a circular ring adapted to force the shell walls inwardly and pass over the outer bead, said beads being arranged to engage on opposite sides of the ring to retain it on the shell, and a longitudinally movable lining for the shell adapted when in normal position under the beads to retain the shell in the expanded condition and cause the beads to hold the ring on the shell.

70 5. In a lamp fixture, a lamp socket shell having longitudinal slits in its open end, a lining for said shell, a shade holder frame comprising a ring, and securing means on the shell cooperating with said lining to lock the ring to the shell comprising a pair of spaced annular ribs extending across said slots and adapted to receive said ring between them.

75 6. In a lamp fixture, a lamp socket shell, a movable relatively stiff lining for said shell, a shade holder frame comprising a ring, yieldable means on the shell cooperating with the ring to secure the frame to the shell, and said lining being arranged to retain said securing means in holding position to lock the ring to the shell.

80 7. In a lamp fixture, a lamp socket shell, a comparatively stiff and rigid insulating lining for said shell, a shade holder frame comprising a ring, and laterally movable securing means on said shell cooperating with said ring to secure the holder to the shell and held in holding position by said lining.

85 In testimony whereof I affix my signature.
